BOLT PULLER

Griffin W. Gray and Charles B. Wade,
Roanoke, Va.

Application September 18, 1945, Serial No. 617,103

3 Claims. (Cl. 254—18)

1

This invention relates to a screw pulling device. An object of this invention is to provide a pulling device which is designed especially for pulling lag screws from railroad ties. At the present time the lag screws, after being in use for a period of time, become frozen in the tie and cannot be pulled therefrom so that the lag screw is first broken at the upper nut end thereof and is then driven through the tie. This procedure destroys the lag screw and of course requires a new lag screw for insertion in the tie.

It is therefore an object of this invention to provide a puller which is designed for a lag screw as embodied in our co-pending application Serial No. 616,688 filed September 17, 1945, and which will readily remove or pull the lag screw from the tie without injury to the screw.

Another object of this invention is to provide a puller which includes a housing enclosing an elongated toothed rack bar and a rock lever carrying a pawl which is engageable with the rack so that rocking of the lever will move the rack endwise or upwardly and simultaneously pull the screw from the tie.

A further object of this invention is to provide a puller of the tie which includes an improved chuck and may rotate relative to the rack bar so that the screw may unthread from the tie as it is being pulled.

With the foregoing objects in view, and others which may hereinafter more fully appear the invention consists of the novel construction, combination and arrangement of parts, as will be more specifically described, and illustrated in the accompanying drawings, wherein are shown embodiments of the invention, but it is to be understood that changes, variations and modifications may be resorted to which fall within the scope of the invention as claimed.

In the drawings:

Figure 1 is a detailed front elevation broken away and a view of a puller constructed according to an embodiment of this invention;

Figure 2 is a vertical section taken substantially on the line 2—2 of Figure 1;

Figure 3 is a sectional view taken on the line 3—3 of Figures 1 or 2;

Figure 4 is a sectional view taken on the line 4—4 of Figure 1;

Figure 5 is an end elevation of the bolt head socket embodied with this holder.

Referring now to the drawings, the numeral 10 designates generally an elongated housing which is formed with an elongated cylindrical body 11

having a lever housing 12 extending from the upper end thereof.

The housings 11 and 12 have slidably mounted therein an elongated rack bar 13 formed with teeth 14 on one side thereof. The bar 13 has secured to its lower end a socket member 15 formed with an internally threaded socket 16 and the member 15 is formed with an annular rib 17 which slidably engages the inner surface of the housing member 11.

The socket member 15 is offset from the rack member 13 a sufficient degree to provide for the slideable engagement of the opposite outer edges of the bar 13 with the housing 11. A bolt head socket member or chuck 18 is detachably mounted in the threaded socket 16 and extends downwardly from the socket member 15. The chuck 18 includes a cylindrical body 19 which is formed with a lengthwise extending slot 21 which communicates with a larger slot 22 thereby forming a substantial T-shaped slot by means of which a flanged bolt head member 23 may be engaged with the chuck member 18. The chuck member 18 includes an inner wall 24 which has extending upwardly therefrom a threaded stud 25 which is threaded into the socket 16.

The rack member 13 is moved lengthwise into housings 11 and 12 and in operative position is moved upwardly by means of a double toothed dog or pawl 26. The pawl 26 is rockably carried by a rock lever 27 which is pivotally mounted as at 28 between the side walls 29 of the lever housing 12. The lever 27 is formed with a transversely disposed arcuate channel 30 within which the round inner end portion 31 of the pawl 26 is adapted to rockably engage. In this manner the pawl 26 is inserted in the channel 30 from one end of the channel 30, thereby eliminating use of a pintle or shaft for the pawl.

The pawl 26 has extending therefrom a pair of wings or ears 32 which engage on opposite sides of the rack bar 13 so as to thereby hold the pawl 26 against lateral movement. The pawl 26 also has extending from one side thereof a pin 33 with which one end of a spring 34 is engaged. The opposite end of the spring 34 is secured to an eye 35 or the like which is carried by the side wall 36 of the lever housing 12.

The side walls 29 of the housing 12 are formed with openings 37 so that the pawl 26 may be manually raised to released position with respect to the rack bar 13, so that the rack bar may be freely moved downwardly. The rack bar 13 is limited in its downward movement by means of a stop 55 washer or lug 38 which is secured by fastening

means 39 to the upper end of the rack bar. A U-shaped or looped handle 40 is secured to the upper wall 41 of the housing 12 so that the device may be held in vertical position during the operation of the lever 21.

It will be understood that the chuck 18 may be designed for receiving a polygonal nut head in which case the opening 22, which is the larger opening or slot, will extend straight rearwardly for a substantial distance and the side walls of the opening will hold the nut head of the bolt against turning movement.

In the use and operation of this device, the chuck member 18 is engaged with the flanged head 23 of the bolt, the chuck being initially extended from the lower end of the cylindrical housing 11. The housing 11 is then lowered until the lower or open end thereof engages the upper side of the tie or tie plate, whereupon the rock lever 21 is vertically rocked, thereby raising the rack bar 13. Inasmuch as the bolt or lag screw 23 is formed with a spiral shank the pulling of the bolt or screw 23 will cause rotation thereof.

Where the head of the bolt or lag screw is round, this head may rotate freely in the chuck 18. However, where the bolt head 23 is formed as a nut and is held against rotation relative to the chuck 18, the latter may rotate relative to the socket 16, being partially unthreaded therefrom with the endwise movement of the rack. However, as the spiral threads on the lag screw are of such pitch as to form about $2\frac{1}{2}$ complete turns for the length of the lag screw, the stud 25 may rotate for two complete turns in the socket 16 without withdrawing the stud 25 a sufficient degree to injure the threads of the stud or the socket.

With a pulling device as hereinbefore described, the lag screws which were usually broken when withdrawn from the ties may be removed without danger to the lag screw and will eliminate the present practice of breaking the upper end of the lag screw and then driving the embedded portion of the screw through the tie.

When the screw is driven through the tie it is necessary to plug the old hole and then re bore the plug to receive the new lag screw. This procedure not only consumes time but also requires a new lag screw. With the puller as hereinbefore described and with a lag screw as embodied in our co-pending application the lag screw will unthread from the opening as it is withdrawn, leaving a clean threaded opening to receive the same lag screw.

What we claim is:

1. A puller comprising an elongated hollow member formed with a cylindrical housing and a

pawl housing extending from said cylindrical housing, a socket member slideable in said cylindrical housing, a toothed rack fixed to said socket member in offset relation whereby one side of said rack will slidably engage both housings, a rock lever carried by said pawl housing, a pawl carried by said lever engaging said rack for moving said rack in one direction and a chuck carried by said socket, said socket being formed with 10 interior threads, and an externally threaded stud carried by said chuck for detachably and rotatably coupling said chuck to said socket.

2. A puller comprising an elongated tubular housing, a toothed rack slideable in said housing, 15 a rock lever carried by said housing, a pawl carried by said lever engaging said rack, said rack having a threaded socket in one end thereof, and a chuck threaded into said socket, said chuck including a round body rotatably engaging in said housing and having an opening in its outer end, 20 said body also having an opening through one side thereof, and a threaded stud extending from the inner end of said body threadably and rotatably engaging in said socket, whereby said chuck 25 may turn in said socket when a screw threaded article is being pulled.

3. A puller comprising an elongated tubular housing, a toothed rack slideable in said housing, 30 a rock lever carried by said housing, said lever having a transverse groove in the inner end thereof, a pawl carried by said lever engaging said rack, said pawl including a rounded end 35 rockably engaging in said groove and insertable in said groove from one end thereof, said rack having a threaded socket in one end thereof, and a chuck threaded into said socket, said chuck including a round body rotatably engaging in said housing and having an opening in its outer end, 40 said body also having an opening through one side thereof, and a threaded stud extending from the inner end of said body threadably and rotatably engaging in said socket whereby said chuck may turn in said socket when a screw threaded article is being pulled.
